UNITED STATES PATENT OFFICE.

FRED H. ROBERTS, OF WILMINGTON, MASSACHUSETTS.

DESIGN FOR A JAR.

48,653.

Specification for Design.

Patented Feb. 29, 1916.

Application filed December 1, 1915. Serial No. 64,595. Term of patent 7 years.

To all whom it may concern:

Be it known that I, FRED H. ROBERTS, a citizen of the United States, residing at Wilmington, in the county of Middlesex and State of Massachusetts, have invented a new, original, and ornamental Design for Jars, of which the following is a specification, reference being had to the accompanying drawing, forming part thereof.

The figure is a view in elevation of a jar, showing my new design.

I claim:

The ornamental design for a jar, as shown.

FRED H. ROBERTS.
